(57) **CLAIM**

The ornamental design for a portable paper pulping assembly, as shown and described.

DESCRIPTION

FIG. 1 is an upper perspective view of a portable paper pulping assembly;

FIG. 2 is a top view of the portable paper pulping assembly as shown in FIG. 1;

FIG. 3 is a first side view of the portable paper pulping assembly as shown in FIG. 1;

FIG. 4 is a rear view of the portable paper pulping assembly as shown in FIG. 1;

FIG. 5 is a front view of the portable paper pulping assembly as shown in FIG. 1;

FIG. 6 is a second side view of the portable paper pulping assembly as shown in FIG. 1; and,

FIG. 7 is an upper perspective view of the portable paper pulping assembly as shown in FIG. 1 with all compartments shown at least partially open.

The bottom is flat and devoid of surface ornamentation. The shade lines shown in the drawings indicate the character and contour of surfaces represented and should not be confused with surface ornamentation.
